UNITED STATES PATENT OFFICE.

CHARLES M. BURGESS, OF NEW BRITAIN, CONNECTICUT, ASSIGNOR TO THE RUSSELL & ERWIN MANUFACTURING COMPANY, OF SAME PLACE.

SHEET-METAL LOCK-CASE.

SPECIFICATION forming part of Letters Patent No. 412,365, dated October 8, 1889.

Application filed July 18, 1889. Serial No. 317,876. (No model.)

To all whom it may concern:

Be it known that I, CHARLES M. BURGESS, a citizen of the United States, residing at New Britain, in the county of Hartford and State 5 of Connecticut, have invented certain new and useful Improvements in Sheet-Metal Lock-Cases, of which the following is a specification.

My invention relates to improvements in sheet-metal lock and latch cases, and the main 10 objects of my improvement are to lessen the cost of production and to produce a case that is specially adapted for a Janus-faced lock.

In the accompanying drawings, Figure 1 is a side elevation of my lock-case. Fig. 2 is a 15 sectional view of the same on line $x-x$ of Fig. 1. Fig. 3 is a rear elevation thereof. Fig. 4 is a corner elevation showing the front and bottom edges. Fig. 5 is a plan view, on a reduced scale, of the blank for one of the plates; 20 and Fig. 6 is a like view of the blank for the companion plate.

The plate A, which I may term the "lock-plate," I form from a rectangular blank having notches or recesses 7 7 at two corners and 25 a central notch 8 at its rear edge. It is also provided with the ordinary holes, &c., for the various parts of the lock and latch, which may be changed according to the particular lock to be produced. The companion plate B, which 30 I may term the "cap-plate," is formed with notches at each corner, two of them 9 9 being of the same width as the notches 7 7 in the plate A, and the other notches 10 10 being wider. The rear edge is also provided with a 35 projection 11 for entering the notch 8 in plate A. The blanks for these plates are bent up on two sides substantially on the broken lines indicated in Figs. 5 and 6 to form flanges, the blank being preferably swaged or struck 40 up to give the broad sides of the case an ornamental effect and to stiffen the same, as shown. The flanges 12 12 on the plate A are at the front and rear edges of the case, while the flanges 13 13 on the plate B are at the top 45 and bottom edges. The notches 7 7 and 9 9 are about half the width of each of said flanges, while the notches 10 10 are about the same width as said flanges. The two parts of the

case are then put together, with the flanges of one part entering the spaces between the 50 flanges of the other parts, so as to form a complete box or case. The ends of the rear one of the flanges 12 of plate A enter and fill the notches 10 10 of the plate B, while the notches 7 7 and 9 9 and ends of the flanges 13 13 of 55 plate B and the front flange 12 of the plate A fit into each other and form rabbeted front corners, all as shown in Fig. 4. While I prefer to rabbet or notch the flanges at the front and rear edges in the particular manner shown, 60 it is evident that all of the corners may be rabbeted in the manner shown for the front edge of the case or for the rear edge.

By my improvements the case is neatly and cheaply formed of only two pieces of sheet 65 metal, thereby avoiding riveting and several other operations usually required in the production of sheet-metal lock-cases. At the same time my lock-case is substantially alike on both sides, and is therefore specially 70 adapted for a Janus-faced lock.

I claim as my invention—

1. The herein-described sheet-metal lock-case, consisting of two plates, each provided with flanges on two opposite side edges and 75 fitted together, with the said flanges of each plate covering the edge of the case at the unflanged edges of the companion plate, substantially as described, and for the purpose specified.

2. The herein-described sheet-metal lock-case, consisting of two plates, each provided with flanges on two opposite side edges and fitted together, with the said flanges of each plate covering the edge of the case at the unflanged edges of the companion plate, the corners of the case being notched at the ends of 85 said flanges, with the ends of the interlocking flanges received in said notches and forming rabbets, substantially as described, and for 90 the purpose specified.

CHAS. M. BURGESS.
